ADVERTISING DEVICE

Albert H. Christensen, Oakland, Calif.

Application March 13, 1939, Serial No. 261,593

1 Claim. (Cl. 40—104)

This invention relates to improvements in advertising devices and has particular reference to a device for displaying signs, commodities and the like and the ability to change the displayed matter at frequent intervals.

A further object is to produce a device which is economical to manufacture, simple in construction, one wherein the parts will not be easily deranged, and a device which is readily portable.

10 Other objects and advantages will be apparent during the course of the following description.

In the accompanying drawings forming a part of this specification and in which like numerals are employed to designate like parts throughout 15 the same,

Fig. 1 is a front elevation showing a portion thereof broken away.

Fig. 2 is a fragmentary perspective view of the cam and release mechanism,

20 Fig. 3 is a top plan view of the cam and pickup mechanism,

Fig. 4 is a top plan view of Fig. 1,

Fig. 5 is a detail showing the manner in which the revolving arm carries the display sign, but 25 one sign holder being shown,

Fig. 6 is a fragmentary detail view showing a side elevation of the cam and pickup mechanism,

Fig. 7 is a similar view showing the cam and release mechanism,

30 Fig. 8 is a fragmentary detail view showing the retaining hook,

Fig. 9 is a perspective view of the release hook, and

35 Fig. 10 is an enlarged cross sectional view on the line 10—10 of Fig. 7.

In the accompanying drawings wherein for the purpose of illustration is shown a preferred embodiment of my invention, the numeral 5 designates a substantially circular casing in which my mechanism is mounted. This casing has a semi-circular glass 6 through which the displays are viewed. Extending from the top to the bottom and in the axis of the casing 5 is a hollow shaft 7 through which a shaft 8 extends. This shaft is driven by a motor 9 or in any suitable manner. Pivots connected to the hollow shaft 7 for swinging movement about the same, is a plurality of plates 11. These plates are provided 45 with upper and lower angular spacers 12, and the lower spaces may be in the form of trays for receiving commodities to be displayed. The construction thus far described is merely a display stand having a plurality of leaves, both 50 sides of which may be viewed as they are revolved

around a central shaft. This structure is common and has no part in my invention.

My invention consists of a pickup and release mechanism which is actuated by the shaft 8. By reviewing Figs. 4 and 5 it will be noted that a 5 substantially semi-circular track 13 is secured to bracing supports 14 and 16 for the upper ends of the shafts and the outer ends of the supports are fixed to the casing, as best shown in Figure 4. Secured midway between its ends to the upper 10 end of the shaft 7 to be carried thereby is an arm 17 that has pivoted thereto members 18 and 19, each of which carries a U-shaped member 21. It will be noted as best shown in Figure 7, that the outer free end portions of the pivoted members 18 and 19 are bent for disposal in spaced relation to the arm 17. This arrangement permits the ends to engage the cam extremity 22 of the semi-circular track 13 (see Fig. 2). Pivoted adjacent the cam 22 is a latch 23 which engages 20 the plates 11 as they are moved in a clockwise direction, the action of this latch being obvious from viewing Fig. 8. Pivoted adjacent the opposite end of the track 13 is a releasing latch 24. This latch has a plate 26 which is engaged by the 25 end of the arm 17 as the same moves in a clockwise direction (see Fig. 3). This engagement raises the latch 24 and releases a plate 11 just at the time that the pivoted member 19 of Figure 3, is over the plate 11 and about to drop from the end 27 of the track 13 for disposing the U-shaped member 21 of the pivoted member 19, in straddling position about the upper end of the plate 11. As a result of this construction and assuming that the motor 9 is running continuously the shaft 8 rotates carrying with it the arm 17. As this arm 17 moves off the end of the track 13 as observed in Fig. 3, the pivoted member 19 will drop so that the depending ends of the U-shaped member 21 will straddle the plate 11 just 30 at the time that the latch 24 is raised by the end of the arm 17 engaging the plate 26. As the arm continues to move it will carry the plate 11 from the position A to the position B. This drive of the plate is illustrated in Fig. 2. As soon as the 35 arm 17 approaches the cammed end 22 of the track 13 the pivoted member 18, or 19 as the case may be, will be lifted, thus drawing the ends of the U-shaped member 21 out of engagement with the plate 11. However, just previous to this action the latch 23 has functioned to hold the plate 11 against any possibility of retrograde movement.

It will, therefore, be seen that my device picks up a plate, moves it through substantially an arc 55

of 180° and releases the plate automatically, accomplishing this change at definite periods.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

10 Having thus described my invention, I claim:

In an advertising device, a plurality of plates pivotally supported for movement about a central axis, a semi-circular track positioned above said plates, an arm rotatably carried above said

plates, pivoted members secured to the ends of said arm for travel on said track, U-shaped members secured to said pivoted members and capable of alternately engaging and releasing each of said plates in consecutive order as said arm is rotated for carrying said plates about a portion of said axis, latches for said plates and mounted adjacent each end of said track, one of said latches being engaged by said arm, whereby said plates will be individually released from the latter latch to be contacted by said U-shaped members to move said plates into engagement with the other of said latches.

ALBERT H. CHRISTENSEN.
